UNITED STATES PATENT OFFICE

127,154

DESIGN FOR A GOBLET OR SIMILAR ARTICLE

Charles W. Carlson, Pittsburgh, Pa.

Application March 4, 1941, Serial No. 99,347

Term of patent 3½ years

To all whom it may concern:

Be it known that I, Charles W. Carlson, a citizen of the United States, residing at Pittsburgh, county of Allegheny, in the Commonwealth of Pennsylvania, have invented a new, original, and ornamental Design for a Goblet or Similar Article, of which the following is a specification, reference being had to the accompanying drawing, forming a part thereof, in which:

Figures 2 and 3 are horizontal sectional views taken along the lines II—II and III—III, respectively, of Figure 1.

I claim:

The ornamental design for a goblet or similar article, substantially as shown.

CHARLES W. CARLSON.
